Attorney

UNITED STATES PATENT OFFICE.

CHARLES A. SCHNEIDER, OF CHICAGO, ILLINOIS.

VEIL CLASP.

Application filed February 3, 1922. Serial No. 533,867.

To all whom it may concern:

Be it known that I, CHARLES A. SCHNEIDER, a citizen of the United States, residing at Chicago, in the county of Cook and State 5 of Illinois, have invented new and useful Improvements in Veil Clasps, of which the following is a specification.

This invention relates to veil clasps, the primary object of the invention being to 10 provide a clasp of simple and economical construction which may be readily used to properly secure veils upon the heads and around the hair and hats of ladies in such manner that they are held positively 15 against becoming deranged or detached, and wherein the veil always presents a neat and attractive appearance.

A further object of the invention is to provide a clasp so constructed as to minimize the opportunity of breakage or 20 stretching the webbing of the veil, regardless of the number of times the veil is used with the clasp, and wherein the ends of the veil may be properly held out of sight 25 so that a neat and attractive appearance at the point of meeting of the veil ends is at all times presented.

A still further object is to provide a clasp of the character and for the purposes 30 stated which combines simplicity of construction with readiness of operation and cheapness of manufacture, yet which will prove thoroughly practical and efficient in use.

35 The invention consists of the features of construction, combination and arrangement of parts, hereinafter fully described and claimed, reference being had to the accompanying drawing, in which:

40 Figure 1 is a rear elevation of a lady's head and illustrating as applied thereto a clasp embodying the invention,

Figure 2 is an enlarged rear elevation of the improved clasp,

45 Figure 3 is an end elevation of the clasp, and

Figure 4 is a longitudinal edge view of the clasp.

Referring now more particularly to the 50 drawing, the body of the clasp is indicated at 5, and may be formed of any suitable material, such as celluloid, bone, composition, or, if desired, of precious metal. This body 5 may be of any suitable size and 55 shape, and may be plain or ornamented as desired. The size of this body, however

is preferably sufficient to cover from view the ends of a veil meeting in the back of the head dress of the wearer.

The body 5, in the present instance, is of 60 substantially oval shape and is thin and flat, and projecting from the rear face thereof in spaced parallel relation and near one end of this body is a pair of lugs or ears 6, having aligned apertures to receive a hinge 65 pin 7 connecting the inner end of a clasp bar 8 between the said ears. This clasp bar extends parallel with the longitudinal axis of the body and is engageable at its free end beneath a hook member 9 disposed 70 near the opposite end of the said body. The clasp bar 8 is formed of pliable metal or other material having bending or distortive qualities such as to enable the same to be hooked beneath or disengaged from the 75 member 9 as required. The lugs 6 and hook 9, as well as the clasp bar 8, may all be formed of material similar to that of which the body 5 is constructed.

The edges of the body 5 and also the 80 ears 6 and hook 9, as well as the bar 8, are all rounded and made perfectly smooth so as to offer no obstruction for the webbing of the veil to become engaged. The portion of the bar 8 disposed between the ears 6 and 85 hook 9 is broadened and of generally elliptical form, and the longitudinally curved (convexly curved) edges thereof are shaped in the form of flanges offset inwardly toward the body 5, giving the bar a concavo- 90 convex form in cross-section, and these edges are waved or corrugated as at 10. The outermost extremities of the corrugated flange portions project beyond the concaved inner face of the bar and, by reason of the 95 concavo-convex cross-sectional form of the bar, brought to lie close to the rear face of body 5 when the bar 8 is engaged at its free end beneath the hook 9, so that 100 thicknesses of the veil or webbing will be firmly impinged by and clamped between such edges of the said bar and the said body.

In practice, the veil will be properly draped upon the face and head of the 105 wearer, and the ends thereof brought together in the rear of the wearer's head, whereupon these ends are engaged snugly between the bar 8 and the body 5, the bar being hooked beneath the member 9. These 110 ends are therefore securely held properly positioned and with the veil adequately ten-

2
sioned, and such unsightly ends are hidden from view.

While the above is a description of the invention in its preferred embodiment, it is to be understood that variations in the construction and arrangement of parts may be resorted to if desired, without departing from the spirit of the invention as defined by the claim.

10 Having thus fully described my invention, I claim:

15 A veil clasp comprising a substantially flat body of approximately oval outline form, a resilient bar hinged at one end to the one face of the body for movement toward and from said face, and a fastener for securing the free end of the bar to the body, said bar being of materially less length and width than the body, whereby the ends of a

20 veil may be brought to lie and to be clamped between the bar and the said face of the body, and the bar and veil ends covered by

the body and concealed from the view of an observer looking toward the reverse face of the body, the bar between its ends being of 25 substantially elliptical outline form and transversely bowed and having its concaved side facing the body so as to dispose the longitudinal edges of the bar in close clamping proximity to the body when the bar is 30 in secured position while disposing the central portion of the bar a greater distance from the body to provide an increased nesting space for the reception of the veil ends therebetween, each of said longitudinal 35 edges of the body being longitudinally fluted to provide a plurality of blunt convexly curved bearing surfaces to clamp the underlying veil end against the body without penetrating or liability of tearing the delicate network of the same.

In testimony whereof I affix my signature.

CHARLES A. SCHNEIDER.
